UNITED STATES PATENT OFFICE.

CHARLES ALBERT BATES, OF VERNON HILL, VIRGINIA.

TORPEDO-FENDER.

1,259,341.

Specification of Letters Patent. Patented Mar. 12, 1918.

Application filed March 15, 1917. Serial No. 155,049.

To all whom it may concern:

Be it known that I, CHARLES ALBERT BATES, a citizen of the United States, residing at Vernon Hill, in the county of Halifax and State of Virginia, have invented certain new and useful Improvements in Torpedo-Fenders; and I do declare the following to be a full, clear, and exact description of the invention, such as will enable others skilled in the art to which it appertains to make and use the same.

My invention relates to that class of devices intended to protect ships against total destruction or even injury from torpedoes and one object is to provide means of this class which will not only prevent the torpedo from striking the vessel but which will trap the same so that it may be taken aboard if required.

Another object of the invention is to provide a fender offering little resistance to the water when extended for use and capable of inward folding when the ship is out of a danger zone such as that recently declared by Germany and embracing the waters adjacent the British Isles, Italy, France and adjoining countries.

With the foregoing general objects in view, the invention resides in the novel features of construction and unique combinations of parts to be hereinafter fully described and claimed, the descriptive matter being supplemented by the accompanying drawings which constitute a part of this specification and in which:

Figure 1 is a side elevation of a vessel giving a diagrammatic illustration of the manner in which the improved fender is applied;

Fig. 2 is an enlarged side elevation of one section of the fender;

Fig. 3 is a vertical transverse section of the vessel equipped with the invention;

Fig. 4 is an enlarged sectional view cut horizontally through one section of the fender; and,

Fig. 5 is a sectional perspective view of one of said sections.

In the drawings above briefly described a ship S is shown equipped with the improved fender, said fender consisting of a plurality of longitudinally disposed sections 1 located on the opposite sides of the vessel.

Each section 1 includes a preferably rectangular vertical plate 2 of one piece of sectional metal construction as occasion may

demand, said plate being supported at a suitable elevation, in respect to the water level, by chains or the like 3 whose upper ends may be wound around windlasses on the ship, around cleats, or secured in place in any other preferred manner. Bridle chains 4 extend beneath the ship and connect the lower edges of the plates 2 on the opposite sides of the vessel as shown most clearly in Figs. 1 and 3. By this arrangement, the sections 1 may be slipped over either the front or rear end of the ship in pairs in harness fashion and may then be secured in place by the chains 3. It is not necessary to apply the fender in this manner, however, since the chains 4 could well be connected to the plates 2 after the latter have been properly positioned.

Pivoted either directly to the upper portion of each plate 2 or to a bar 5 secured thereto, are horizontal vertically swinging links 6 whose outer ends are pivoted at 7 to the several sections 8 of the guard proper, one of said sections 8 being provided for each plate 2. Each section of the guard preferably consists of a plurality of vertical bars 9 and horizontal bars 10 integrally joined or otherwise united at their crossing points, the outer sides of all of said bars being beveled substantially to knife edges 11 so as to present no surfaces at right angles to the course of a torpedo directed toward the side of the vessel, it being intended that even should the pointed nose of the torpedo strike one of the bars 9 or 10, that it shall glance therefrom and wedge between said bars as indicated by the dotted lines in Fig. 3.

For supporting the guard sections 8 and for raising them when required to cause the links 6 to move said sections inwardly to the dotted position of Fig. 3, cables 12 are connected to the upper edges of said sections, adjacent the ends thereof, said cables, (or chains if desired), being by preference wound around windlasses carried by the ship.

For holding the lower portions of the several guard sections 8 in properly spaced relation with the ship, horizontally swinging arms 13 are pivoted either directly to the lower edge of the plates 2 or within channel iron bars or the like 14 permanently secured to said plates, the latter construction being preferable. An upper and lower series of arms 13 are shown in the present embodi-

ment of the invention and the alternate arms of the lower series are provided with forks or other guides 15 slidably receiving the lower ends of the vertical bars 9. The intervening arms of said lower series and all of the arms of the upper series are free of guides such as 15 and merely abut the inner sides of said bars 9.

The arms 13 of the upper and lower series 10 are by preference connected by vertical rods 16 and all of said rods are in turn connected by longitudinal bars 17 so that movement of said bars will swing all of the arms 13 parallelogrammatically to the dotted line 15 position of Fig. 4, it being understood that one bar 17 is provided for each of the sections 1.

Any preferred means may be employed for shifting the bars 17 after the guard sections 8 have first been raised to remove the 20 lower ends of their bars 9 from the guides 15, but cables or the like 18 will in most cases be provided for this purpose. Two cables 18 are provided for each bar 17, said cables 25 being connected with said bar at points spaced from the ends thereof and extending obliquely from these points to sheaves 19 secured to the plates 2. From the sheaves 19 the cables 18 rise to suitable operating 30 means carried by the vessel.

By constructing the fender in the manner shown and described, it may be quickly and easily folded when its use is unnecessary yet when required, said fender may be quickly 35 extended into operative position and so held by the arms 13 and the guides 15, it being understood that said arms must be swung outwardly to operative position before the guard sections 8 are simultaneously lowered 40 and moved outwardly, this being necessary in order that the lower ends of the bars 9 may be received in the guides 15. Stops 20 are preferably carried by the channel iron bars 14 to check the movement of the arms 45 13 when said arms are in the proper position for performing their functions.

The improved fender, when projected, will serve as an effective guard for preventing the noses of torpedoes from striking the hull 50 of the ship and even though they may be exploded by contact with the guard 8, little or no injury will result due to the fact that the guard is spaced sufficiently from the vessel to greatly decrease the effect of the 55 explosion thereon. It is to be also considered that the plates 2 are substantially double the thickness of the hull and thus greatly resist the inward pressure caused by the explosion.

60 On account of the advantages above pointed out, the specific construction shown and described constitutes the preferred form of the fender. It is to be understood, however, that within the scope of the invention as 65 claimed, numerous variations may be made

without sacrificing the principal advantages. For instance, although the construction shown is preferably provided for securing the plates 2 in position, they might well be held in place detachably or permanently by 70 any other preferred means. Similarly, in some types of the invention, the guards 8 could well be pivoted directly to the sides of the ship instead of connecting them with the plates 2 and securing the latter in place. 75

I claim:—

1. A torpedo fender comprising a rigid vertically disposed guard and means for moving said guard vertically from its operative position, means connected with the upper 80 edge of said guard for normally spacing the same from the ship and for moving it inwardly when said guard is moved vertically, and horizontally foldable means for spacing the lower edge of the guard from the ship. 85

2. A torpedo fender comprising a rigid vertically disposed guard and means for moving said guard vertically from its operative position, means connected with the upper edge of said guard for normally spacing the same from the ship and for moving it inwardly when said guard is moved vertically, and horizontally foldable means for spacing the lower edge of the guard from the ship, said foldable means having guides for 90 receiving parts of said guard to prevent folding of said means until the guard is disengaged from said guides. 95

3. A torpedo fender comprising a rigid vertically disposed guard and means for 100 moving said guard vertically from its operative position, means connected with the upper edge of said guard for normally spacing the same from the ship and for moving it inwardly when said guard is moved vertically, horizontally swinging pivoted arms for 105 spacing the lower edge of the guard from the ship, and means for swinging said arms inwardly and outwardly.

4. A torpedo fender comprising a rigid 110 vertically disposed guard, and means for raising said guard from its operative position, means connected with the upper edge of said guard for normally spacing the same from the ship and for moving it inwardly 115 when said guard is raised, horizontally swinging pivoted arms for spacing the lower edge of the guard from the ship, guides on the outer ends of said arms receiving parts of said guard to prevent inward swinging of said arms until said guard is disengaged from said guides, and means for swinging said arms inwardly and outwardly. 120

5. A torpedo fender comprising a protecting plate and means for securing it along the side of a ship, a rigid vertically disposed guard spaced outwardly from said plate, means for moving said guard vertically from its operative position, means connect- 125

ing the upper edges of said guard and plate for moving the former inwardly when moved vertically from said operative position, and foldable means for spacing the lower edge of the guard from said plate.

5 6. A torpedo fender comprising a protecting plate and means for securing it along the side of a ship, a rigid vertically disposed guard spaced outwardly from said plate, means for moving said guard vertically from its operative position, means connecting the upper edges of said guard and plate for moving the former inwardly when moved vertically from said operative position, and horizontally foldable means carried by the lower edge of said plate for spacing the corresponding edge of the guard outwardly therefrom.

10 7. A torpedo fender comprising a protecting plate and means for securing it along the side of a ship, a rigid vertically disposed guard spaced outwardly from said plate, means for moving said guard vertically from its operative position, means connecting the upper edges of said guard and plate for moving the former inwardly when moved vertically from said operative position, and horizontally foldable means carried by the lower edge of said guard for spacing the corresponding edge of the guard therefrom, said foldable means having guides receiving parts of said guard to prevent folding of said means until said guard is disengaged from said guides.

15 8. A torpedo fender comprising a protecting plate and means for securing it along the side of a ship, a rigid vertically dis-

posed guard spaced outwardly from said plate, means for moving said guard vertically from its operative position, means connecting the upper edges of said guard and plate for moving the former inwardly when moved vertically from said operative position, horizontally swinging arms pivoted to the lower edge of said plate for spacing the corresponding edge of said guard outwardly therefrom, and means for swinging said arms inwardly.

20 9. A torpedo fender comprising a protecting plate and means for securing it along the side of a ship, a rigid vertically disposed guard spaced outwardly from said plate, means for moving said guard vertically from its operative position, means connecting the upper edges of said guard and plate for moving the former inwardly when moved vertically from said operative position, horizontally swinging arms pivoted to the lower edge of said plate for spacing the corresponding edge of the guard outwardly therefrom, the outer ends of said arms having guides to receive parts of said guard to prevent folding of said arms until said guard is disengaged from said guides, and means for swinging said arms inwardly and outwardly.

25 In testimony whereof I have hereunto set my hand in the presence of two subscribing witnesses.

CHARLES ALBERT BATES.
